UNITED STATES PATENT OFFICE.

MOSES F. PATTON, OF TUSCALOOSA, ALABAMA, ASSIGNOR TO A. SCHRADER'S SON, INCORPORATED, OF BROOKLYN, NEW YORK.

DUST-GUARD FOR PNEUMATIC-TIRE VALVES.

1,288,155.

Specification of Letters Patent.

Patented Dec. 17, 1918.

Application filed July 20, 1916. Serial No. 110,333.

To all whom it may concern:

Be it known that I, MOSES F. PATTON, a citizen of the United States of America, residing at Tuscaloosa, in the county of Tuscaloosa and State of Alabama, have invented certain new and useful Improvements in Dust - Guards for Pneumatic - Tire Valves, of which the following is a specification.

My invention relates to improvements in dust guards for the valve stems of pneumatic tires, and its objects are to simplify and reduce the cost of construction of devices of this character, to effectively exclude water from gaining access to the inner tube, to reduce to a minimum the number of parts, and to adapt them to give ready access to the tire valve for testing or inflating the inner tube.

According to my invention I provide a tubular thimble having a body portion adapted to be passed through the felly and to be expanded or fastened in place therein, its inner end being made slightly tapered to effect a water tight fit in the felly opening without the use of a washer.

A further feature of my invention is to make integral with such thimble a means for attaching the dust cap thereto so as to leave the valve stem free of connection to the dust cap or thimble.

My invention further comprises the details of construction and arrangements of parts which in their preferred embodiments only are hereinafter more particularly described, reference being had to the accompanying drawings, in which:—

Figure 1 is a vertical sectional view through the wheel felly with my dust guard in place therein.

Fig. 2 is a detail view of the thimble.

Fig. 3 is a detail view of the dust cap.

Fig. 4 is a view similar to Fig. 1, showing a modification of my invention.

Similar reference numerals refer to similar parts throughout the drawings.

Referring to the embodiment of my invention illustrated in Figs. 1 and 2, I show a wheel felly 1 of any standard design having a metal rim 2 mounted thereon, both parts having alining radial openings to form a socket for the reception of the body portion 3 of a tubular thimble. This body portion is provided at one end with a taper enlargement 4 which joins an annular flange 5, beyond which is a threaded extension 6. This

integral thimble is adapted to be driven from the inside outwardly through the opening in the felly, until its shoulder 5 abuts the felly, when its taper portion 4 will be wedged so tightly in the felly opening 60 as to make a water tight fit therein. The outer end of the thimble body is beaded or expanded into engagement with the metal rim 2, whereby the thimble is permanently and rigidly held in place. A dust cap 7 is 65 provided having at its inner end a threaded portion 8 adapted to screw onto the threaded portion 6 of the thimble. Only a small number of threads are required for the portions 6 and 8 whereby the dust cap can be 70 quickly and easily removed and at the same time the valve stem can be taken out and replaced without the necessity of removing the dust cap.

Referring to Fig. 4, I herein illustrate a 75 thimble having a body portion 9 provided with a taper enlargement 10 and an annular flange 11, which parts are similar respectively to the parts 3, 4 and 5 of the thimble illustrated in Fig. 2, except that the flange 80 11 is made thicker than the flange 5. The flange 11 carries a tubular extension 12 having near the flange an annular groove 13 and having its outer end beveled at 14. A dust cap 15 is provided at its open end with an 85 enlarged shoulder 16 having preferably the same diameter and thickness as the flange 11 and provided internally with a channel or groove in which is seated an annular compressible packing 17. The inner bore of the 90 cap 15 is of such diameter as to make a snug fit over the cylindrical extension 12 and the packing 17 normally projects into the bore of the dust cap so that it must be contracted and compressed into its groove before the 95 cap can be forced in either direction over the unreduced portion of the extension. This packing when the cap is seated against the flange 11 will expand into the groove 13 and hold the dust cap against displacement 100 while permitting it to be drawn off or replaced with a quick strong pull or push axially of the thimble. This method of mounting the dust cap on the tubular base member is shown and claimed specifically 105 in Patent No. 1,162,099, granted to me November 30, 1915.

My invention provides an integral thimble member which gives a water proof protection to the inner tube and affords a base 110

СОЧИНО ТИНТАЧ ГЕНТАС ДЕНИ

member to which the dust cap can be quickly and easily connected without interference with the tire valve. to be expanded to hold the thimble in permanent water-tight joint in the felly, substantially as described.

Having thus described my invention, what I claim as new and desire to secure by Let-

ters Patent, is:—

8.1. A dust cap for pneumatic tire valves comprising a removable cap, and a thimble adapted for permanent attachment to the wheel felly, said thimble having at its inner end a cap retaining means and at an intermediate point a felly engaging shoulder integral with the thimble and having its outer end adapted to be expanded to permanently secure the thimble in position in the felly and hold said shoulder in permanent water tight engagement with the felly.

12. A dust guard attachment for pneumatic tire valves comprising a thimble adapted for permanent attachment to the wheel felly, a dust cap, means to detachably mount the dust cap on the inner end of the thimble, an integral shoulder formed on the thimble, which at the base of said shoulder is made conical, the outer end of the thimble being adapted to project through the felly, when the shoulder on the thimble has been forced into engagement with the wheel felly, and

16. on, there being registered openings in said rim and felly, of an integral tubular thimble having an elongated smooth body portion adapted to be inserted through the openings in the felly with a close fit and having a conical enlargement near its inner end terminating in an annular shoulder surrounding the thimble, said thimble having its conical end forced into the inner end of the felly opening until the said shoulder engages the felly to seal said felly opening, in which position the outer end of the thimble is in position to be expanded into the metal rim to hold the thimble in fixed position in the felly, and a dust cap detachably connected to the inner end of the thimble, substantially as described.

18. In testimony whereof I affix my signature in presence of two witnesses.
